Primary Examiner — Thomas Johannes(74) *Attorney, Agent, or Firm* — Oblon, Spivak, McClelland, Maier & Neustadt, L.L.P.(57) **CLAIM**

The ornamental design for a seasoning package, as shown and described.

DESCRIPTION

FIG. 1 is a front elevational view of a seasoning package showing our new design;

FIG. 2 is a right side elevational view thereof, the left side elevational view being a mirror image of the side view shown;

FIG. 3 is a bottom plan view thereof, the top plan view being a mirror image of the plan view shown;

FIG. 4 is a rear elevational view thereof; and,

FIG. 5 is a bottom, front, and right side perspective view thereof.

The broken lines in the FIGS. 1-5 depict unclaimed subject matter only and form no part of the claimed design.
